UNITED STATES PATENT OFFICE.

SAMUEL S. SHOREY, OF HOPEDALE, MASSACHUSETTS, ASSIGNOR TO GEORGE DRAPER & SON, OF SAME PLACE.

IMPROVEMENT IN HOLDERS FOR SPINNING-RINGS.

Specification forming part of Letters Patent No. 122,335, dated January 2, 1872.

To all persons to whom these presents may come:

Be it known that I, SAMUEL S. SHOREY, of Hopedale, of the county of Worcester and State of Massachusetts, have made a new and useful invention for Supporting the Ring of a Spinning-Frame; and do hereby declare the same to be fully described in this my specification and represented in the accompanying drawing, of which—

Figure 1 is a top view; Fig. 2, a bottom view; Fig. 3, an edge elevation; and Figs. 4 and 5, transverse sections of my said ring retainer or supporter. Fig. 6 is a top view; Fig. 7, a bottom view; and Figs. 8 and 9, transverse sections of it and a spinning-ring as applied to it.

The said retainer is specially applicable to duplex race-ring—that is, one having the form, as represented in the drawing, or provided with two circular races, *a b*, united by a short tube, neck, or connection, *c*, such composing the ring *A*. The retainer *B*, as shown, consists of a flat annulus, having holes *d d* through it or arranged in it, as shown, to receive the screws by which it is to be fastened to the rail. The said annulus on its inner edge is sawed into or split in four places radially, or in or about in parallel lines, to the depth of about the sixteenth of an inch. Next two opposite arcal portions *f f* of the annulus are turned upward to obtuse angles with the upper face of the annulus, leaving between them two arcal bearings or rests *g g* for the support of a spinning-ring, *A*, when sprung between the two parts or jaws *ff*. The two jaws are curved to fit to and grasp the periphery of the lower race of the ring *A* in manner as shown in the drawing, the inherent elasticity of the jaws or of them and the rest of the supporter sufficing to hold the ring down upon the sup-

porter and admit of its being readily removed therefrom, as occasion may require. The curved form of the arcal jaws suffices to cause them to hold the ring in a manner to prevent any lateral movement of it.

I make no claim to the split ring-retainer made as represented in the United States Patent No. 117,934, wherein the holding lip goes entirely around the ring while the latter is resting on the rail. With my retainer the ring does not rest on the rail but in the retainer, or the parts or rests *g g* thereof, which is an advantage, as it admits of the connection of the ring and the supporter as well while the two may be off as while they may be on the ring-rail, thereby enabling the rings and supporters to be preserved from being improperly intermixed while off the rail so as to get misfitted. It enables a party when purchasing the rings and supporters to be sure of a proper fit of each ring to its supporter, the two being purchased together. Furthermore, my invention saves all necessity of splitting the ring-supporter to enable it to be sprung upon the ring, thus avoiding all danger of the ring becoming detached from the supporter in case of the accidental loosening of its confining screw.

I claim—

The spinning-ring supporter or retainer as made or provided with the arcal jaws *ff* and the intermediate arcal ring rests *g g*, arranged together and with the remainder of the annulus *B*, substantially in manner and to operate as described.

SAMUEL S. SHOREY.
